Primary Examiner — Richard E Chilcot

(74) Attorney, Agent, or Firm — Birch, Stewart, Kolasch & Birch, LLP

(57) **CLAIM**

The ornamental design for an ice cream maker, as shown and described.

DESCRIPTION

1. Ice cream maker

1.1 : Perspective

1.2 : Front

1.3 : Back

1.4 : Left

1.5 : Right

1.6 : Bottom

1.7 : Top

1.8 : Reference view showing a state of use

(Continued)

The parts shown by means of broken lines in the reproductions are not part of the claimed design.

1 Claim, 8 Drawing Sheets
